UNITED STATES PATENT OFFICE.

MILES G. NIXON, OF CHICAGO, ILLINOIS, AND OBERLIN SMITH, OF BRIDGETON, NEW JERSEY.

GAME APPARATUS.

1,319,355.

Specification of Letters Patent.

Patented Oct. 21, 1919.

Application filed March 27, 1918. Serial No. 224,922.

To all whom it may concern:

Be it known that we, MILES G. NIXON, of Chicago, in the county of Cook and State of Illinois, and OBERLIN SMITH, of Bridgeton, in the county of Cumberland and State of New Jersey, have invented a certain new and useful Improvement in Game Apparatus, and do hereby declare that the following is a full, clear, and exact description 10 thereof.

Our invention relates to games of the nature of ten pins and more particularly to table apparatus comprising ten-pins and a suspended missile or ball and generally 15 stated our object is to provide an apparatus capable of use by two or more persons and which is readily adaptable to the number of players, and to this end our invention consists in the game apparatus constructed 20 substantially as hereinafter specified and claimed.

In the accompanying drawings:

Figure 1 is a perspective view of apparatus embodying our invention arranged for 25 three persons to participate in the game;

Fig. 2 is a top plan view illustrating another form of our invention and arranged for four players;

Fig. 3 is a perspective view illustrating 30 yet another construction embodying our invention.

Briefly described our apparatus comprises a platform or board consisting of a section shown as in the form of a segment 10 for 35 each player (there being preferably four such segments) a group of ten-pins 11 for each segment, and a missile or ball 12 hung by a flexible device such as a chain or cord 13 at the center of the segments, the cord being of such length that when the ball is 40 thrown by a player from his side of the board, it may reach and strike the ten pins of an adversary, the ball being suspended by a swivel so that it may swing around the 45 circle of players. The ball suspending device is preferably in the form of a post or mast 14 which rises from the central portion or section 15 of the board to which the post is detachably connected and to which the 50 segments are also detachably connected, as shown in Figs. 1 and 2, these detachable connections being for the purpose of enabling the apparatus to be taken down and packed in small compass, and in the case of 55 the segments to enable the number in use to

be varied so as to consist of either two, three or four, depending on the number of players and to enable them to be placed at equal distances apart whether the number be two, three or four. Referring to Figs. 1 and 2, 60 the central section 15 of the board has a circular or polygonal contour and in its edge there are radial holes or sockets 16 so arranged that there are four that are ninety degrees apart and three one hundred and 65 twenty degrees apart, and in the inner edge of each segment is a similar hole or socket 17. As shown in Fig. 1, a flat distance block 18 is interposed between the periphery of the central section 15 and each segment said distance block having at opposite ends a tenon or pin 19 adapted to enter one of the holes in the central board section 15, and a hole in one of the segments and thus the board 70 is set up for the game. The matter of assembling and taking apart the board involves nothing more than the thrusting of the tenons in the holes of the central section 75 15 and the segments, and their separation.

It is desirable to prevent the dead men or 80 the pins toppled over falling to the floor when the apparatus is used upon a table, where ordinarily it will be placed and which approximates the diameter of the table. For this purpose we attach to the outer rim of 85 each segment an upstanding flange or fence 20 which preferably inclines outward and upward so as to efficiently serve the purpose without risk of the clothes of the player catching upon the edge thereof, as is apt to 90 happen if the fence is vertical. The fence is made of suitable sheet material, and the ends for each segment terminate in such form that when the apparatus is in a knocked-down condition, one segment with 95 its fence can readily nest within the other.

To facilitate placing the ten-pins or men in position, the segments have slight circular depressions or sockets 21, each of a diameter to readily receive the base of the 100 ten pin.

The detachable distance and connecting piece between each segment and the central portion 15 of the board instead of being a block as shown in Fig. 1 may be a simple 105 round rod 22 as shown in Fig. 2. It will be evident that the distance piece as a separate part need not be employed because, as for example, a table may be specially made having a circular top with a central hole or 110

socket to receive the lower end of the ball suspending mast, and holes in the top toward the edge of the table top to receive tenons on the undersides of the segments.

- 5 As shown in Fig. 3 the segments may be hinged or pivoted together one above the other so that when not in use all may be folded or swung on the pivotal connection so that one lies directly above the other and 10 the lateral extent of all is no greater than the dimensions of one and they are opened out or swung upon their pivots when the game is to be played, the desired number being opened out whether two, three or four. 15 Thus the board consists of the desired number of units say four composed of a central portion 150, an arm or spoke 151 radiating therefrom, and the ten pin supporting segment 152 at the extremity of the arm, 20 these three parts being made of one piece of material which may be sheet metal or other thin sheet material, and the central portions 150 being joined by a pivot 153.

The employment of the segments for the 25 ten pins for the respective players is highly desirable in that the field or place occupied by each player and his men is very distinctly separated from the others and hence confusion is obviated.

- 30 By reason of the suspension of the ball from a central mast not only is the apparatus given a very simple and attractive form, but since the ball is free to swing around in an orbital path, it is possible most 35 advantageously to multiply the number of players above two.

Having thus described our invention what we claim is:

1. A game apparatus comprising several 40 groups of ten-pins, a support for each group, a ball suspending post about which

the supports are situated, said supports being shiftable to vary the distance between them according to the number of players to participate in the game, each support being of a size to hold all the pins for each player.

2. A game apparatus comprising several groups of ten-pins, a support for each group, a ball suspending post about which 50 the supports are situated, said supports being shiftable to vary the distance between them according to the number of players to participate in the game, each of said supports having a fence outside the row of ten-pins when placed thereon.

3. A game apparatus comprising groups of ten-pins, a suspended ball about which the groups are situated, and a board comprising a central section and ten-pin supporting sections separately connected with the central section and each ten-pin supporting section being of elongated form and spaced from the central section beyond its mid-portion, each supporting section being 65 of a size to hold all the pins for each player.

4. A game apparatus comprising a board composed of a central section and ten-pin supporting sections radiating therefrom, said central and pin-supporting sections being independent parts, means extending from the pin-supporting sections to the central section, that hold the sections in spaced relation for playing purposes, each supporting section being of a size to hold all the 70 pins for each player, and a central ball-suspending post rising from said central section.

In testimony that we claim the foregoing we have hereunto set our hands.

MILES G. NIXON.
OBERLIN SMITH.
